CLAIM

The ornamental design for a cooking assistant accessory device, as shown and described.

DESCRIPTION

FIG. 1 is a top angled view of a first embodiment of a cooking assistant accessory device showing our new design;

FIG. 2 is a bottom angled view thereof;

FIG. 3 is a front view thereof;

FIG. 4 is a rear view thereof;

FIG. 5 is a top view thereof;

FIG. 6 is a bottom view thereof;

FIG. 7 is a left-side view thereof;

FIG. 8 is a right-side view thereof;

FIG. 9 is a bottom view showing an alternative position thereof; and,

FIG. 10 is a bottom view showing an alternative position thereof.

The broken lines showing features of the design are for the purpose of illustration only and form no part of the claimed design.
